DESIGN FOR A COAT

Morris D. Metzger, New York, N. Y.

Application June 16, 1939, Serial No. 85,512

Term of patent 3½ years

To all whom it may concern:

Be it known that I, Morris D. Metzger, a citizen of the United States of America, residing in New York city, in the Borough of Manhattan, county and State of New York, have invented a new, original, and ornamental Design for a Coat, of which the following is a specification, reference being had to the accompanying drawing, forming part hereof, wherein—

Figure 1 is a front view of a coat showing my new design.

Figure 2 is a rear view of the coat shown in Figure 1.

The characteristic feature of my design resides in the combination on the coat disclosed of the specific shaped slot seams extending along the front, rear and sleeve portions, as shown, which seams are opened at the front neckline, and closed at the rear neckline.

I claim:

The ornamental design for a coat, substantially as shown and described.

MORRIS D. METZGER.
